UNITED STATES PATENT OFFICE.

ABRAM P. ANDREWS, OF DOVER, NEW HAMPSHIRE, ASSIGNOR OF ONE-HALF
TO THOMAS T. DODGE, OF PORTLAND, MAINE.

STORM-WINDOW FASTENER.

SPECIFICATION forming part of Letters Patent No. 443,348, dated December 23, 1890.

Application filed October 25, 1889. Serial No. 328,210. (No model.)

To all whom it may concern:

Be it known that I, ABRAM P. ANDREWS, of Dover, in the county of Strafford and State of New Hampshire, have invented certain new and useful Improvements in Storm-Window Fasteners; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in storm-window fasteners.

It is designed to take the place of the common screws now in use.

It gives a firmer grip and requires no screw-holes in the window-frame.

In the drawings herewith accompanying and making a part of this application, Figure 1 is a view of my improved fastener. Fig. 2 is a section of a window and frame, showing method of applying my improved fastener, and same letters refer to like parts.

In said drawings, *a* represents the outside or storm window; *b*, the outside casing-strip; *i*, the jamb; *j*, the lower window, and *k* the bead between the upper and lower windows.

The storm-window sash has holes therein at suitable distances apart for the fasteners to pass through.

The fastener has a long body or shank *c*, on one end of which is a thread *g*, adapted to receive a thumb-nut *d*, and on the other end a lug *e* to grip the outside casing, as shown in Fig. 2. The end of the shank near the lug is flattened and extends out at the side beyond the line of said shank, thus forming a projection *f*, which gives a broad base to rest against the casing and to prevent the fastener from turning when being tightened by said thumb-nut.

To apply my improved fastener, first insert the fastener in the outside window-sash from the inside, with the lug turned in, as shown by dotted lines in Fig. 2, place the window in position, turn fastener half round, and apply thumb-nut until the lug grips against the casing-strip, as shown in Fig. 2. The flat projection *f*, pressing against the edge of the casing, prevents the fastener from turning and the lug from losing its grip while the thumb-nut is being tightened.

To remove the window, first loosen the nut, 55 then force the fastener inward until the projection *f* is beyond the casing-strip, and turn the fastener until the lug is in the position indicated by dotted lines in Fig. 2. The projection should be on that side which will prevent the fastener from turning when the nut is being tightened. The fastener will turn readily when the nut is loosened without pressing inward, there being no projection on the opposite side to prevent it. Unless the fasteners could be turned round to the position shown in dotted lines the lugs would not pass by the casing-strip.

The fasteners being once inserted in the window-sash, it will be unnecessary to remove them again, and they may be put away with the window, and thus be always ready for use. Where the upper sash comes directly against the casing-strip *b*, a recess may be made in said strip sufficiently deep to receive the lug 75 and allow it to turn therein.

The advantages of my improved fastener consist in the ease with which it may be applied, the greater tightening-power, and consequently closer joint than can be secured by 80 means of a screw, and in the avoidance of the necessity for the unsightly screw-holes in the window-easing, which not only disfigure the window, but also, by reason of the said holes rotting out during the warm weather in summer, render new holes necessary every time the window is put on.

Having thus described my invention and its use, what I claim, and desire to secure by Letters Patent of the United States, is— 90

The combination, with a storm-window having holes in the sash, of a series of fasteners adapted to pass through said holes, each fastener having on one end a lug adapted to grip the window-easing and on the other a thread 95 and thumb-nut, and having a shank straight on one side and with a flat projection on the other, substantially as and for the purposes set forth.

In testimony that I claim the foregoing as 100 my own I affix my signature, in presence of two witnesses, this 14th day of October, A. D. 1889.

ABRAM P. ANDREWS.

Witnesses:

ELGIN C. VERRILL,
T. T. DODGE.
